HEAT INSULATED HANDLE FOR AUTO-MOBILE RADIATOR CAPS

Simon Huber, Brooklyn, N. Y.

Application January 20, 1950, Serial No. 139,729

6 Claims. (Cl. 220—24)

1

This invention relates to new and useful improvements in automobile radiator caps, and more particularly to an attachment for known radiator caps whereby the latter can be handled while extremely hot without discomfort to the handler.

The radiator cap used almost universally in modern automobiles comprises a metal cap member having internal lugs for engagement with an annular flange on the radiator intake pipe and external lugs or extensions by which the member can be twisted to remove it from said pipe. Inside of said member gasket means are resiliently urged against the end of said pipe and effectively seal the same.

During the operation of an automobile, the radiator, and, therefore, the metal radiator cap, become extremely hot, so that when removing the latter to replenish the water in the radiator, the hands are every often burned.

The principal object of the invention, therefore, is to provide an attachment for such radiator caps whereby they can be removed and replaced without danger of burning the hands.

Another object of the invention is to construct said attachment in the form of a handle of heat insulating material such as wood, the handle being affixed to the radiator cap.

Still another object of the invention is the provision of a modified handle which may be kept in a convenient location in filling stations, etc., and which can be engaged with such radiator caps to remove the same quickly and easily, the cap remaining engaged with the handle until it is replaced on the radiator intake pipe.

For further comprehension of the invention, and of the objects and advantages thereof, reference will be had to the following description and accompanying drawings, and to the appended claims in which the various novel features of the invention are more particularly set forth.

Fig. 1 is a perspective view of a radiator cap, having the handle of the invention affixed thereto, the view being taken from beneath the cap.

Fig. 2 is a partial sectional view of the cap-handle combination taken substantially on the line 2—2 of Fig. 1, but with the parts turned to have the handle at the top.

Fig. 3 is a plan view of the handle removed from the cap.

Fig. 4 is a side elevation of the handle removed from the cap.

Fig. 5 is a transverse sectional view showing the handle constructed in accordance with a modification of the present invention and applied to a radiator cap.

Fig. 6 is a perspective view similar to Fig. 1, but illustrating a modified form of connection between the cap and the handle.

2

Fig. 7 is a plan view, partly broken away, of the handle of Fig. 6.

Fig. 8 is a side elevation of the handle of Fig. 7, and

Fig. 9 is a perspective view of the modified connecting means.

The handle, according to the first form of the present invention shown in Figs. 1 to 4, is illustrated applied to a conventional automobile radiator cap consisting of a sheet metal cap member 10 having downturned peripheral edges 11. Radially oppositely disposed inturned ears 12 are provided for cooperation with an annular flange 9 on the intake pipe 19 of a radiator (Fig. 2) in securing the cap thereon. For turning the cap to engage it on said pipe, or to remove it therefrom, the cap member is provided with radially opposite extensions 13 which can be grasped by the fingers to twist the cap. The means for sealing the pipe comprise a gasket member 14 secured to a spring-like bell disc 15, the said gasket and disc being secured to the cap member by a center rivet 16 which acts through a washer 17 on the gasket.

The construction is such that when the ears 12 are engaged with the flange of the intake pipe, the gasket is forced firmly against the upper end of the pipe by disc 15 and effectively seals said pipe.

In its simplest form, the handle of the present invention includes a disc 18 of wood or other heat insulating material, having approximately the same diameter as the cap member 10, and having radially opposite extensions 20 of the same general shape as the extensions 13 of the cap member. The extensions 20 are connected by a cross bar 21 which preferably is integral with the disc 18 and has longitudinal grooves 22 in its sides for grasping the same with the fingers.

Each end edge of the cross bar 21 is slotted as at 23, to receive the inturned upper end 24 of a strip 25 of springy metal, such for example, as, berillium copper, said strip extending downward in abutting engagement with the end edge of said cross bar and being secured thereto by a nail 26 or the like. The strip 25 extends below the disc 18 and has its lower end turned in as at 27 for the purpose to be described presently.

The lower face of disc 18 is adapted to abut the upper edge of cap member 10 and in order to accommodate the head of rivet 16 the center of said disc is provided with an indentation 28, see Figs. 2 to 4.

The construction is such that the disc 18 is placed in abutting relationship with the cap member 10 and turned relative thereto to engage the inturned lower ends 27 of the strips 25 beneath the extensions 13 of the cap. Said lower ends then are bent upward slightly inside of said extensions (Fig. 2) to effect a permanent en-

gagement between the parts. Thus, if the cross bar 21 be grasped in the hand and turned, the cap member 10 turns also. It will be seen, therefore, that there has been provided an extremely simple handle for the radiator cap, which handle will not become hot and burn the hands when being manipulated thereby.

In a modified form of the present invention shown in Fig. 5, additional means are provided for securing the cap and the handle together, said means comprising a plurality of rivets 30 passed through the cross bar 21, the disc 18 and the cap member 10.

In other respects the modified form of the invention is similar to that described in connection with Figs. 1 and 4 and like reference numerals are used to identify like parts in all of the views.

In another modification of the invention, the handle is not permanently secured to the cap member, but rather is so constructed as to be engaged therewith for purposes of removal and replacement of the cap, and then disengaged to be stored in a convenient location for future use. This form of the invention is particularly beneficial to filling station attendants or the like who are repeatedly forced to remove and replace hot radiator caps while servicing automobiles.

In this form of the invention, the strips 25' each are provided with a lateral extension or ear 31, abutting the side of the extension 28 of disc 18 and also the cross bar 21 to which it is secured by nails 32 or the like (Figs. 6 and 9). The extensions or ears 31, of the two strips 25' are located on opposite sides of the cross bar 21 so that if the disc 18 be placed in abutting relationship with the cap member 10 and then turned anti-clockwise to engage the inturned lower ends 27' of strips 25' beneath the extensions 13 of said cap member, the lower ends of the ears 31 of said strips come into contacting relationship with the clockwise sides of the extensions 13 of the cap member. Further anti-clockwise rotation of the handle will, through said ears 31, rotate the cap member and free it from the radiator intake pipe. When said cap member has been removed the in-turned ends 27' of strips 25' hold it clasped to the disc 18.

To replace the cap 10 on the pipe, the cap, still secured to the handle, is placed in position on the pipe and turned clockwise through said handle to secure it in place. If it should happen that the inturned ends 27' of strips 25' slide out from beneath the extensions 13 of the cap before the latter is fully engaged on the pipe, the handle is lifted slightly, turned anti-clockwise and the ears 31 of said strips engaged with the anti-clockwise side of the cap extensions 13, the handle then being turned clockwise to force the cap into proper engagement through the ears 31. The handle is then removed and placed in a convenient location awaiting further call for its services.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new, and desire to secure by United States Letters Patent is:

1. The combination with an automobile radiator cap comprising a cap member having down-

turned peripheral edges, radially opposite in-turned ears on said edges, by which the cap is secured on the intake pipe of a radiator, radially opposite extensions of said cap member whereby the latter can be turned manually to free it from, or secure it on, the pipe, said downturned edge also spanning said extensions, a pipe sealing gasket, a spring-like bell disc to tension said gasket against the end of the pipe, a washer engaging the under face of said gasket, and a center rivet acting through said washer to secure said gasket and disc to said cap member, of a heat insulating handle for said radiator cap comprising a disc of heat insulating material of approximately the same diameter as said cap member and in abutting relationship therewith radially opposite extensions on said disc, said extensions having approximately the same outline as the extensions of said cap member, a radial cross bar integral with the disc and connecting said extensions, grooves in the sides of said cross bar for engagement by the fingers, and means for securing said handle disc in abutting relationship with said cap member.

2. The combination with an automobile radiator cap comprising a cap member having downturned peripheral edges, radially opposite in-turned ears on said edges, by which the cap is secured on the intake pipe of a radiator, radially opposite extensions of said cap member whereby the latter can be turned manually to free it from, or secure it on, the pipe, said downturned edge also spanning said extensions, a pipe sealing gasket, a spring-like bell disc to tension said gasket against the end of the pipe, a washer engaging the under face of said gasket, and a center rivet acting through said washer to secure said gasket and disc to said cap member, of a heat insulating handle for said radiator cap comprising a disc of heat insulating material of approximately the same diameter as said cap member and in abutting relationship therewith radially opposite extensions on said disc, said extensions having approximately the same outline as the extensions of said cap member, a radial cross bar integral with the disc and connecting said extensions, grooves in the sides of said cross bar for engagement by the fingers, a lateral slot in each of the end edges of said cross bar, a metal strip secured to and abutting each end edge of said cross bar, and having its upper end turned in to engage in said slot, the lower end of each said strip extending below the handle disc and the extension of said cap member and having its lower end turned inward beneath said extension to secure the handle and cap together and upward between the downturned edges of said extension to prevent relative rotative movements of the handle and the cap.

3. The combination with an automobile radiator cap comprising a cap member having downturned peripheral edges, radially opposite in-turned ears on said edges, by which the cap is secured on the intake pipe of a radiator, radially opposite extensions of said cap member whereby the latter can be turned manually to free it from, or secure it on, the pipe, said downturned edge also spanning said extensions, a pipe sealing gasket, a spring-like bell disc to tension said gasket against the end of the pipe, a washer engaging the under face of said gasket, and a center rivet acting through said washer to secure said gasket and disc to said cap member, of a heat insulating handle for said radiator cap comprising a disc of heat insulating material of

approximately the same diameter as said cap member and in abutting relationship therewith radially opposite extensions on said disc, said extensions having approximately the same outline as the extensions of said cap member, a radial cross bar integral with the disc and connecting said extensions, grooves in the sides of said cross bar for engagement by the fingers, a lateral slot in each of the end edges of said cross bar, a metal strip secured to and abutting each end edge of said cross bar, and having its upper end turned in to engage in said slot, the lower end of each said strip extending below the handle disc and the extension of said cap member and having its lower end turned inward beneath said extension to secure the handle and cap together and a plurality of rivets passed through said cross bar, said handle disc and said cap member to fix the handle and the cap relative to one another.

4. The combination with an automobile radiator cap comprising a cap member having downturned peripheral edges, radially opposite in-turned ears on said edges, by which the cap is secured on the intake pipe of a radiator, radially opposite extensions of said cap member whereby the latter can be turned manually to free it from, or secure it on, the pipe, said downturned edge also spanning said extensions, a pipe sealing gasket, a spring-like bell disc to tension said gasket against the end of the pipe, a washer engaging the under face of said gasket, and a center rivet acting through said washer to secure said gasket and disc to said cap member, of a heat insulating handle for said radiator cap comprising a disc of heat insulating material of approximately the same diameter as said cap member and in abutting relationship therewith radially opposite extensions on said disc, said extensions having approximately the same outline as the extensions of said cap member, a radial cross bar integral with the disc and connecting said extensions, grooves in the sides of said cross bar for engagement by the fingers, a lateral slot in each of the end edges of said cross bar, a metal strip secured to and abutting each end edge of said cross bar, and having its upper end turned in to engage said slot, the lower end of each said strip extending below the handle disc and the extension of said cap member and having its lower end turned inward beneath said extension to secure the handle and cap together temporarily, an ear on each said strip secured to and abutting the clockwise side of said cross bar and said disc and extending downward into contacting relationship with the clockwise side of said cap member extensions.

5. The combination with an automobile radiator cap comprising a cap member having downturned peripheral edges, radially opposite in-turned ears on said edges, by which the cap is secured on the intake pipe of a radiator, radially opposite extensions of said cap member whereby the latter can be turned manually to free it from, or secure it on, the pipe, said downturned edge also spanning said extensions, a pipe sealing gasket, a spring-like bell disc to tension said gasket against the end of a pipe, a washer engaging the under face of said gasket, and a center rivet acting through said washer to secure said gasket and disc to said cap member, of a heat insulating handle for said radiator cap comprising a disc of heat insulating material of approximately the same diameter as said cap member and in abutting relationship therewith radially

opposite extensions on said disc, said extensions having approximately the same outline as the extensions of said cap member, a radial cross bar integral with the disc and connecting said extensions, grooves in the sides of said cross bar for engagement by the fingers, a lateral slot in each of the end edges of said cross bar, a metal strip secured to and abutting each end edge of said cross bar, and having its upper end turned in to engage in said slot, the lower end of each said strip extending below the handle disc and the extension of said cap member and having its lower end turned inward beneath said extension to secure the handle and cap together temporarily, an ear on each said strip secured to and abutting the clockwise side of said cross bar and said disc and extending downward into contacting relationship with the clockwise side of said cap member extensions, whereby on turning the handle anti-clockwise, the cap member is turned by said ears to free it from the pipe.

6. The combination with an automobile radiator cap comprising a cap member having downturned peripheral edges, radially opposite in-turned ears on said edges, by which the cap is secured on the intake pipe of a radiator, radially opposite extensions of said cap member whereby the latter can be turned manually to free it from, or secure it on, the pipe, said downturned edge also spanning said extensions, a pipe sealing gasket, a spring-like bell disc to tension said gasket against the end of the pipe, a washer engaging the under face of said gasket, and a center rivet acting through said washer to secure said gasket and disc to said cap member, of a heat insulating handle for said radiator cap comprising a disc of heat insulating material of approximately the same diameter as said cap member and in abutting relationship therewith radially opposite extensions on said disc, said extensions having approximately the same outline as the extensions of said cap member, a radial cross bar integral with the disc and connecting said extensions, grooves in the sides of said cross bar for engagement by the fingers, a lateral slot in each of the end edges of said cross bar, a metal strip secured to and abutting each end edge of said cross bar, and having its upper end turned in to engage in said slot, the lower end of each said strip extending below the handle disc and the extension of said cap member and having its lower end turned inward beneath said extension to secure the handle and cap together temporarily, an ear on each said strip secured to and abutting the clockwise side of said cross bar and said disc and extending downward into contacting relationship with the clockwise side of said cap member extensions, whereby on turning the handle anti-clockwise, the cap member is turned by said ears to free it from the pipe, said cap after having been removed from the pipe remaining secured to said handle.

SIMON HUBER.
